UNITED STATES PATENT OFFICE.

EDMONDO MICHELE BORGO, OF TURIN, ITALY.

GEAR CASE WITH MEMBERS OF STAMPED METALLIC PLATE EASILY REMOVABLE AND ADJUSTABLE IN LENGTH.

1,402,044.

Specification of Letters Patent.

Patented Jan. 3, 1922.

Application filed February 25, 1920. Serial No. 361,207.

To all whom it may concern:

Be it known that I, EDMONDO MICHELE BORGO, a subject of the King of Italy, residing at Turin, Italy, have invented certain new and useful Improvements in Gear Cases with Members of Stamped Metallic Plate Easily Removable and Adjustable in Length; and I do hereby declare the following to be a full, clear, and exact description 10 of the invention, such as will enable others skilled in the art to which it appertains to make and use the same, reference being had to the accompanying drawings, and to letters or figures of reference marked thereon, 15 which form a part of this specification.

The present invention has for its object a gear case with members of stamped metallic plate easily removable and adjustable in length, which may be used for any kind of 20 chain transmission, especially for that of automobile vehicles in general and particularly motorcycles.

This gear case consists of two portions, 25 sliding one upon the other, and each composed of two members. The first portion, formed as a case for one of the two sprockets, and two tubular parts for the two sides of the chain, consists of two members of stamped plate, jointed together on a longitudinal plane. The second portion, formed 30 as a case for the other sprocket, consists of two members of stamped plate jointed together on a transversal plane which may be diametral. One of these members is removable to allow of repairs to be made to 35 the chain, and the other is provided with sleeves into which the tubular parts of the first portion slide, with the object of allowing any variation in the length of the case 40 at the moment of the tension adjustment of the chain. In this gear case the two members of each portion are connected, by means of the same fastening members which serve to secure the whole of the gear case to two 45 fixed points of support.

A constructional form of the gear case in accordance with the present invention will be hereinafter described, with reference to the annexed drawing, which is given merely 50 as an example, in its application to the chain drive from the motor to the rear wheel of a motorcycle. It is understood, however, that this application is described and illustrated merely by way of explanation and consequently it in no way limits 55

the application of the object of the invention.

In this drawing:—Fig. 1 gives a general view in side elevation of the application of the gear case to the chain drive of the motorcycle; Figs. 2 and 3 show a gear case in detail on a larger scale in elevation and plan; Fig. 4 shows the gear case in horizontal section and illustrates the manner in which it is secured to the vehicle; Fig. 5 shows in horizontal section the two detached members which compose the first portion of the gear case; Figs. 6 and 7 show the removable members of the second portion of the gear case.

The gear case (see Figs. 1 and 4) consists of two portions, —a—, —b— and —c—. The first consists of the end case —a— and of the two tubular pieces —b— in one piece with the case. The second portion —c—, forming the other end case, is provided with sleeves in which are inserted and made to slide the ends of the tubular pieces —b—. The two cases —a— and —c— are intended to contain the front sprocket —d— and rear sprocket —e—, respectively; of these sprockets the front one —d— is driven by the motor and is keyed to the shaft of the latter or else to the countershaft issuing from the change of speed casing —f—, while the rear one —e— is secured to the hub —g— of the rear wheel —h— of the vehicle. The two tubular pieces —b— which establish the communication between the two cases —a— and —c— are intended to contain the two sides of the chain.

According to the invention, the end case —a— and the tubular pieces —b—, in one piece with it, are composed (see Figs. 2 to 5) of the two members of stamped plate substantially symmetrical with respect to a longitudinal vertical plane —X—X—. These members are adjusted one upon the other. Each of these members has the portions —1^a— and —2^a— stamped in the shape of a cup and destined to constitute the two halves of the front sprocket wheel case —a— and the two portions —1^b— and —2^b— having the shape of a trough and destined to constitute the two halves of each of the two tubular pieces —b—.

The perimetral edge of the member 1^a, 1^b is provided with a projecting flange plate 1 welded thereto and when the two portions a, a and b, b of the case are coupled the 110

perimetral edges are tightly joined by the flange plate 1.

The other case —c—, which is also of stamped plate, consists of two members 3 and 4 secured together following a transversal plane which is preferably diametral —Y—Y—. The rear removable member 4 of the case —c— is provided all around its perimetral adjusting edge, with a projecting flange or plate 4' secured to it for instance by welding, on which the corresponding edge of the other member 3 is tightly jointed. The front member 3 of the case —c— is provided with two sleeves 3', which may be beveled, in which are inserted the ends, which may also be beveled if desired, of the tubular pieces —b—. The front wall of the case —c— is sufficiently enlarged to contain the outer portion of the hub —g— of the wheel 20 —h— and its sprocket —e— and is provided at the center with the opening —c'—, each half of the opening being in one of the two members 3 and 4. The inner wall of the case is provided with a large opening for the free passage of the annular projection —e'—, with which the sprocket —e— is provided, while the two members 3 and 4 of the case are equipped at this point with the flanged edges 3'' and 4'' destined to fit as exactly as 30 possible against the annular projection —e'—, without, however, coming into contact with it.

The securing in their relative positions of the different members of which the gear case is composed and of the gear case as a whole in its place in respect to the sprockets and chain is effected by means of the following arrangement (see Fig. 4).

The bottom wall of the member —1^a—, 40 constituting the rear half of the case —a—, has a wide opening bounded by the edge 1', which is slightly conical, destined to engage with the slightly conical projection —f'— of the casing —f—. The portion 45 —2^a— has on the outside a block 5 secured to it by welding, and having the open eye 5' through which is inserted the stem 6 of a swing-bolt pivoted at 6' to a fixed part,— to the case —f— for instance. On the other 50 hand the milled nut 7, screwed to the threaded end of 6, engages with its hemispherical base 7' the interior of a hemispherical cavity 5'' of the block 5. Owing to this arrangement, by screwing the nut 7 against the block 5, the front member —2^a, 2^b— of the gear case is fixed to the other member —1^a, 1^b—, while the whole of the two members, owing to the fitting of the conical edge 1' upon the conical projection 60 —f'— of the casing —f—, remains secured to the fixed support constituted by the said casing —f—.

On the other hand the two members 3 and 4 constituting the case —c— are assembled 65 together and attached to the frame of the

motorcycle by fixing the front wall of the case centrally between the flange 8' of a sleeve 8 passing through the central opening c' of —c— and the washer 9. This sleeve 8 and the washer 9 are secured in 70 their turn between the fixed axle —i— of the hub —g— and the fork —k— supporting the rear wheel —h— by the customary tightening means which serve to fix the axle —i— of the hub —g—, these means consisting for instance of the screw —m— which is screwed into the axle —i—.

Owing to the form of the gear case as described above it is evident that when the chain is adjusted the gear case is also easily 80 regulated as to length by causing the portion —c— to slide on the tubular pieces —b— slidably supported in the sleeves 3'. Any repairs of the chain can easily be made by simply removing the removable rear 85 member 4 of the case —c—, which can readily be done by slightly unscrewing the bolt —m— which fixes the axle —i— of the hub to the rear bracket —k—. Furthermore the gear case can be completely and quickly dismounted after unscrewing the bolt —m— as well as unscrewing and backward swinging of the bolt 6, 7 as shown by dotted lines in Fig. 4 and, after having removed the chain, the mounting of the different members in their proper places is effected in a manner equally simple and rapid. The gear case described above, owing to the exact fitting of its members, not only protects the chain and sprockets against exterior agencies, but also presents a sufficient tightness to retain efficiently the lubricant which might be introduced to lubricate the chain and sprockets.

I claim:

1. A gear case comprising two gear wheel casings one of which is transversely divided into two portions and one of said portions having sleeves, the other wheel casing having tubular extensions and longitudinally divided into two parts, the ends of said extensions slidably bearing in said sleeves.

2. A gear case comprising two wheel casings, one of which is centrally divided transversely into two portions, one of which portions has two sleeves and the other wheel casing having integral tubular extensions whose ends have sliding bearing in said sleeves, said casing and extensions being longitudinally divided into a front and a rear portion, and said rear portion having a perforated depression.

3. A gear case comprising two wheel casings one of which is transversely divided into two portions, one of which portions has two sleeves; and the other wheel casing having integral tubular extensions whose ends have sliding bearing in said sleeves, said casing and extensions being longitudinally divided into a front and a rear portion,

said rear portion having a central perforated conical depression and said front portion having an open eye, and a bolt pivoted to a stationary machine part to enter said eye to hold the front portion to the rear portion.

4. A gear case comprising two wheel casings, one of which is transversely and centrally divided into two portions, one of which portions has two sleeves, said wheel casing having front and rear central perforations common to both portions, the rear

perforation being in a conical wheel hub receiving depression, a flanged sleeve passing through said front perforation, a 15 washer on said sleeve the front of both portions being clamped between the flange of said sleeve and said washer, and a front wheel casing having tubular extensions having sliding support in said sleeves. 20

In testimony that I claim the foregoing as my invention, I have signed my name.

EDMONDO MICHELE BORGO.
